UNITED STATES PATENT OFFICE.

ALFRED UPTON ALCOCK, OF LONDON, ENGLAND.

ELECTRICAL SIGNALING APPARATUS.

SPECIFICATION forming part of Letters Patent No. 683,872, dated October 1, 1901.

Application filed January 31, 1901. Serial No. 45,411. (No model.)

To all whom it may concern:

Be it known that I, ALFRED UPTON ALCOCK, a subject of the Queen of Great Britain and Ireland, residing at London, England, have invented Improvements in or Relating to Electrical Signaling Apparatus, of which the following is a specification.

This invention relates to various improvements in electrical signaling apparatus of the kind in which the transmitting and receiving instruments are connected by three line-wires and the indicator of the receiving instrument or of each of such instruments, where there are two or more, is caused to move in a corresponding manner to the indicator or other movable part of the transmitting instrument by means of an electric motor, the magnetic field of which is caused to turn or rotate by the action of a commutator forming part of or connected to the transmitting instrument.

The present invention consists in various novel features of construction and combinations and arrangements of parts, all as hereinafter fully described, and pointed out in the claims.

In the accompanying illustrative drawings, Figure 1 is a diagram showing one arrangement of electrical signaling apparatus according to my present invention. Figs. 1^a, 1^b, and 1^c are diagrams showing the working of the apparatus. Figs. 2 and 3 are elevations at right angles to one another, showing one construction of automatic switch. Fig. 4 is a diagram showing a modified arrangement of the signaling apparatus. Fig. 5 is a developed plan view showing part of the transmitter-case. Fig. 6 is a front elevation, and Fig. 7 a section, on the line A A of Fig. 6, showing one construction of receiving instrument according to this invention. Figs. 8 and 9 are similar views to Figs. 6 and 7, showing a modified construction of receiving instrument. Fig. 10 is a similar view to Fig. 7, showing a further modified construction of receiving instrument. Fig. 11 shows, partly in vertical section on the line B B of Fig. 12 and partly in side elevation, and Fig. 12 in front elevation, a transmitting instrument with one construction of commutator according to this invention. Fig. 13 is a rear end elevation, and Fig. 14 a side elevation,

of the commutator shown in Figs. 11 and 12, but drawn to a larger scale, and Fig. 15 is a developed view of the commutator-contacts with insulated segments. Fig. 16 is a diagram showing how the commutator-brushes of the commutator shown in Figs. 11 to 15, inclusive, are preferably connected to an electric battery. Figs. 17, 18, 19, and 20 are diagrams illustrating the operation of the commutator shown in Figs. 11 to 15, inclusive.

In the arrangement of signaling apparatus shown in Fig. 1 the transmitting instrument at *a* is normally disconnected from the line-wires *c*, *d*, and *e*, leading to the receiving instrument at *b*, but is adapted on being operated to send a signal to become automatically connected to the said line-wires by a switch at *f*, provided with a movable indicator *g*, which becomes deflected at this time to indicate that a signal has been sent. The receiving instrument at *b* is provided with a relay at *h*, adapted on a signal being sent by the transmitting instrument to close a local circuit *l* and operate a sounding device *m*. The said receiving instrument is also provided with a short-circuiting device at *n*, whereby the three line-wires *c*, *d*, and *e* can be short-circuited upon themselves, so as to cause the switch at *f* to disconnect the transmitting instrument at *a* from the line-wires and at the same time cause the switch-indicator *g* to return to its normal position. The arrangement is such that upon operating the transmitting instrument at *a* to send a signal the automatic switch at *f* will connect the line-wires *c*, *d*, and *e* to the transmitting instrument and the switch-indicator *g* will be deflected and remain deflected and the sounding device *m* at the receiving instrument at *b* will be operated and remain in operation until an attendant short-circuits the said instrument by means of the short-circuiting device at *n*, whereupon the switch-indicator *g* will return to its normal position, thus indicating to the person in charge of the transmitting instrument that the signal has been received, and the switch *f* will be caused to open the circuit between the transmitting and receiving instruments, and thereby prevent waste of electrical energy, a matter of considerable importance when electric batteries are used as the source of electrical supply,

the pointer of the receiving instrument at *b* remaining opposite the signal last sent until another signal is sent by the transmitting instrument. The switch at *f* may be operated to close the circuit between the transmitting and receiving instruments at *a* and *b* by an electromagnetic device *p*, the circuit of which is adapted to be temporarily closed by the movement of the handle of the transmitting instrument, as hereinafter described, the said circuit between the transmitting and receiving instruments being maintained closed by another electromagnetic device *q* (brought into action by the closing of the said circuit) until the said circuit is short-circuited, as hereinbefore described. The circuit of the electromagnetic device *p* may be provided with a hand-operated switch *r*, whereby it can be opened when desired, so as not to be completed when the transmitting instrument is operated.

Apparatus to operate in the manner set forth can be constructed in various forms.

In the arrangement shown in Fig. 1 the transmitting instrument at *a* comprises a rotary commutator provided with an operating-handle *t* and a pointer *u*, that is arranged to move over a fixed dial *v*, bearing the orders, signals, or other indications (hereinafter called "signals") to be sent. The rotary commutator may be of any suitable kind. In Fig. 1 the commutator comprises two fixed contacts or brushes *w* *x*, that are respectively connected by conductors *w*^a and *x*^a to the opposite poles of an electric battery *y* or other suitable electric generator, and three contacts 1, 2, and 3, that are movable relatively to the fixed contacts *w* and *x*, between which they are mounted to rotate. The movable contacts 1, 2, and 3 in the form of curved metal segments having an angular length of nearly one hundred and twenty degrees each are fixed near together around a cylindrical block 7^a and are respectively connected by three insulated conductors 1^a, 2^a, and 3^a to three insulated collars 4, 5, and 6, carried by the same spindle 7 as the insulating-block 7^a. On the collars 4, 5, and 6, respectively, bear three stationary brushes 8, 9, and 10, that are connected to three conductors 11, 12, and 13, respectively, for connection by the automatic switch at *f*, as hereinafter described, to the three line-wires *c*, *d*, and *e*, respectively, leading to the receiving instrument at *b*. This receiving instrument is of a known kind. It comprises a rotary electric motor having a field-magnet *i* composed of an iron ring wound with three separate pairs of coils *c*', *d*', and *e*', that are respectively connected at one end of the line-wires *c*, *d*, and *e*, and the other ends of which are connected together at the point *j*. The two coils of each pair are arranged in series and diametrically opposite to each other, as shown, and the direction of winding of each pair of coils is arranged to produce opposite poles in the field-magnet ring *i* at right angles to the pair of

coils, and the three pairs of coils are arranged, as shown, so that their resultant fields are angularly displaced sixty degrees apart around the field-magnet ring *i*.

k is the armature of the motor, made light and mounted to rotate within the field-magnet ring *i* and connected to a pointer *k*', arranged to move over a dial *k*², bearing signals corresponding to those on the dial *v* of the transmitting instrument.

The automatic switch at *f* comprises, as shown in Figs. 2 and 3, three upper coils 14, 15, and 16 and three lower coils 17, 18, and 19, wound upon separate horizontally-arranged iron cores 20, provided with polar projections 21, of which there are consequently twelve, arranged in two rows of three each at the front and back of the device. The cores 20 are carried by two side plates *f*', through which their ends project and between which the several coils 14 to 19, inclusive, are located. Between the two rows of polar projections 21 outside one of the plates *f*' is a pivoted armature 22, and between the two rows of polar projections outside the other plate *f*' is a pivoted armature 23. Each of these armatures normally rests upon an adjustable stop 24, above which is an adjustable contact 25. One of the armatures—viz., 22—is permanently connected to the conductor 11 through the coil 17, Fig. 1, and the other armature—viz., 23—is permanently connected to the conductor 12 through the coil 18, the two adjustable contacts 25 above the two armatures 22 and 23 being respectively connected to the line-wires *c* and *d*. One of the upper coils—viz., 14—is connected or adapted to be connected through the hand-operated switch *r*, such as a divided socket and plug, to an electric circuit that comprises the battery *y* and two conductors 26 and 26^a, and which is adapted to be closed each time the transmitter-handle *t*, Fig. 1, is operated to send a signal and to be automatically opened when the pointer *u* of the transmitter is brought opposite a signal on the transmitter-dial *v*. For this purpose the said handle *t* may be provided with an insulated contact 27, that is connected by means of the conductor 26 through the coil 14 and switch *r* to one pole of the electric battery *y*, the other pole of which is connected through the conductor 26^a to a spring-contact arm 28. This spring-contact arm is carried by, but insulated from, the said handle *t* and is arranged to bear against a ring 29, Figs. 1 and 5, that is fixed to the transmitter-case and is formed with cam-like projections 29^a and 29^b, with intervening recesses 29^c, which correspond in position to the central portions of the spaces on the order-dial *v*, that are marked with the orders or signals to be sent. The arrangement is such that when the handle *t* is turned to send a signal the spring-contact arm 28 will be forced against the insulated contact 27 each time it passes a projection 29^a and will spring away from such contact.

each time it comes opposite a recess 29^b—that is to say, when the pointer *u* comes opposite the central portion of an order on the order-dial *v*—so that the circuit including the coil 14 will be closed and opened alternately when the handle *t* is operated to send a signal and will be left open when the pointer *u* stops opposite the signal to be sent. One of the other upper coils—viz., 15—is connected at 10 one end to the line-wire *c* and at the other end, preferably through a resistance-coil 31, to the line-wire *e*. The third upper coil 16 is connected at one end to the line-wire *d* and at the other end, preferably through the said 15 resistance-coil 31, to the said line-wire *e*. The three lower coils 17, 18, and 19 are arranged to respectively form part of the three separate commutator-conductors 11, 12, and 13, whereof 11 and 12 are connected to the respective armatures 22 and 23, as hereinbefore 20 stated, while 13 is directly connected to the line-wire *e* through the coil 19.

Each of the upper coils 14, 15, and 16 is made with a greater number of turns than 25 each of the lower coils 17, 18, and 19, so that when the line-wires *c*, *d*, and *e* are not short-circuited the cores of the upper coils will attract the armatures 22 and 23 with a greater force than the cores of the lower coils and 30 hold them against the contacts 25, whereas when the line-conductors are short-circuited little or no current will pass through the coils 15 and 16 and a larger current will pass through the lower coils 17, 18, and 19, with 35 the result that the cores of these coils will act to pull down the armatures 22 and 23 and so disconnect the commutator-conductors 11 and 12 from the line-wires *c* and *d*. The switch-indicator may consist, as shown in 40 Figs. 1, 2, and 3, of a pivoted pointer *g*, arranged to move over a plate or dial 32 and provided with a soft-iron armature 33, arranged in proximity to two of the cores 20 and pole-pieces 21 of the upper coils 15 and 45 16, Figs. 2 and 3, so as to be operated thereby and move the said pointer over the dial when either or both of the said coils are energized and to be released and allow the said pointer to move back to the zero position when the 50 said coils are short-circuited.

The relay at *h* for closing the local circuit *l* at the receiving instrument at *b*, Fig. 1, may conveniently comprise three coils 63, that are of considerable resistance and are connected 55 star fashion to the line-wires *c*, *d*, and *e* at *c*^a, *d*^a, and *e*^a, respectively, and are connected together at 63^a and have their cores 64 arranged to attract a pivoted armature 52 and close the local circuit *l* through an electric 60 generator 55, a fixed contact 56, and the electric bell *m*, which is arranged on, in, or near to the said receiving instrument.

The short-circuiting device (shown at *n* in Fig. 1) comprises three contact-pins 69, carried by a suitable insulating-holder 70 and connected at the points *c*^a, *d*^a, and *e*^a to the respective line-wires *c*, *d*, and *e*, and a metal

disk or plate 71, that is adapted to be pressed simultaneously into contact with all the said contact-pins 69, so as to short-circuit the said 70 line-wires against the action of a spring 72, which serves to press the said disk or plate 71 when released away from the said contact-pins.

The operation of the apparatus is as follows: Immediately upon turning the handle *t* of the transmitter at *a* to send a signal the circuit of the coil 14 will be completed between the contacts 27 and 28, as hereinbefore described, and the armatures 22 and 23 will 80 be attracted upward against the contacts 25 25^a by the core of the said coil, so as to connect the commutator-conductors 11 and 12 to the line conductors *c* and *d*, respectively, and thereby bring the coils 15 and 16 into action 85 by the current shunted therethrough to hold up the said armatures and also bring the coils 63 of the relay *h* into action to close the local circuit *l* at the receiver, and thereby cause the bell *m* to ring. As the said handle *t* is 90 turned, the pointer *k'* of the receiver will move in exactly the same manner as the pointer *u* of the transmitter, so that both pointers at each moment will be opposite similar signals on their respective dials, as is 95 usual in signal-transmitting apparatus of the kind to which this invention relates and as will be readily understood from Figs. 1^a, 1^b, and 1^c, which are diagrammatic views wherein in the line N S at right angles to each pair 100 of coils *c'*, *d'*, and *e'* in the receiver at *b* represents the direction of the magnetizing force of that pair of coils when traversed by an electric current. The arrow *K'*, *K*², or *K*³ represents the position of the resultant magnetic 105 field of the set of coils *c'* *d'* *e'* when traversed by an electric current, and consequently the position of the armature *k* and pointer *k'* of the receiver, and the small arrows *x'* *x*² *x*³ indicate the direction of the current in the various 110 parts of the circuit for the three different positions of the commutator shown in Figs. 1^a, 1^b, and 1^c.

In Fig. 1 the transmitter is shown disconnected from the receiver and the pointers *u* and *k'* of the two instruments are shown at their top positions. Upon turning the commutator-segments 1, 2, and 3 and the pointer *u* into the position shown in Fig. 1^a the coil 14 will be temporarily energized and caused to raise 120 the armatures 22 and 23, which will then connect the commutator-conductors 11 and 12 to the line conductors *c* and *d*, and thereby energize the coil 15 and cause the same to hold up the armatures, as hereinbefore described, 125 the indicator *g* will be deflected by reason of the armature 33, Fig. 3, being attracted by the core 20 of the said coil 15, the relay-armature 52 will be attracted and complete the local circuit *l* and cause the bell *m* to ring, the 130 pair of coils *d'* of the receiving instrument will be cut out of circuit, and the pair of coils *e'* connected in series with the pairs of coils *c'*, so that the resultant magnetic field set up

by the current flowing through the two pairs of coils e' and c' , when the handle t and pointer u have been turned through an angle of thirty degrees, will be also turned through thirty degrees and into the position indicated by the arrow K' , which also indicates the position of the pointer k' of the receiver. The direction of the current through the various parts of the apparatus in this position of the commutator is indicated by the arrows x' . Upon turning the commutator-segments 1, 2, and 3 and pointer u through another angle of thirty degrees—say into the position shown in Fig. 1^b—the two pairs of coils e' and d' will be connected in parallel with one another and in series with the pair of coils c' , so that the resultant field (indicated by the arrow K^2) will be moved through another thirty degrees, as also will the armature k and pointer k' , which consequently again corresponds in position to the pointer u of the transmitting instrument. In this position of the commutator current will be shunted through both coil 15 and coil 16. The direction of the current through the various parts of the apparatus in this second position of the commutator is indicated by the arrows x^2 . If the commutator-segments 1, 2, and 3 and pointer u be moved through another thirty degrees—say into the position shown in Fig. 1^c—the pair of coils e' will be cut out and the pair of coils d' will be connected up in series with the pair of coils c' , so that the resultant field, (indicated by the arrow K^3), and consequently the armature k and pointer k' , will have been moved through another thirty degrees—that is to say, into a position still corresponding to the pointer u . In this position of the commutator current will also be shunted through the two coils 16 and 15, which will be in series. The course of the current through the various parts of the apparatus in this third position of the commutator is indicated by the arrows x^3 . In this way by rotating the commutator (shown in Figs. 1 to 1^c) through thirty degrees at a time the resultant magnetic field of the coils c' d' e' will, as well understood, be caused to take up twelve successive positions located thirty degrees apart and corresponding to twelve different orders or signals on the transmitter-dial v , and the pointer k' of the receiver will be caused to take up twelve corresponding successive positions over the dial k^2 of the receiver. In each case the bell m will be caused to ring until the three line-wires c , d , and e are short-circuited upon themselves by causing the metal plate 71 of the short-circuiting device to simultaneously bear upon the three pins 69. When this is done, the relay-coils 63 will be short-circuited, with the result that the relay-armature 52 will move automatically into its inoperative position and open the local circuit l and stop the bell. The receiver-coils c' , d' , and e' will also be short-circuited, with the result that the resistance of the circuit through the three line-wires c d e , the commutator-conductors 11,

12, and 13, the commutator, and the battery, will be so far reduced that sufficient current will not pass through the coils 15 and 16 to cause their cores to hold up the armatures 22 and 23 against the pulling-down action of the lower cores 20, surrounded by the coils 17, 18, and 19, which, owing to the reduction in the resistance of the circuit, will be energized by a greater current than before. The lower cores and coils will consequently pull down the armatures 22 and 23 and disconnect the line-wires c and d from the transmitter, and the cores of the coils 15 and 16 being then demagnetized the armature 33 of the indicator g will be released and allow the said indicator to return to its zero position, thus indicating that the signal has been received. In order that the person in charge of the transmitting instrument shall be certain that the order sent has not only been received but has been correctly understood, means may be provided at the receiving-station b , whereby the short-circuiting of the line conductors c , d , and e and the opening of the local relay-bell circuit l is prevented until the pointer of an instrument, which I will call the "reply" instrument, having a signal-dial corresponding to that of the transmitting instrument, has been moved opposite to the signal corresponding to that sent. Fig. 4 shows signal-transmitting apparatus of the kind hereinbefore described with reference to Figs. 1 to 1^c, inclusive, together with a reply instrument for the purpose above mentioned, except as relates to the short-circuiting device shown in Fig. 1, &c. This reply instrument comprises a signal-dial v' , bearing signals corresponding in kind and position to those on the dial v of the transmitter, a pointer u' , that is arranged to move over the said dial v' , a commutator at b' , and an electromagnetic device at b^2 for controlling a local circuit, including an electromagnetic short-circuiting device. The commutator at b' is an exact duplicate of that of the transmitting apparatus at a in Fig. 1 and comprises two fixed brushes w^4 and x^4 , connected to a battery y^2 , corresponding to that of the battery y at the transmitting-station a , and three rotary segmental contacts 1^x, 2^x, and 3^x, that are connected to three commutator-conductors 11^a, 12^a, and 13^a through fixed contacts 8^a, 9^a, and 10^a, and revolving metal rings 4^a, 5^a, and 6^a, which are connected to the rotary contacts 1^a, 2^a, and 3^a by conductors 1^b, 2^b, and 3^b. The said electromagnetic device at b^2 comprises three iron cores 75, each wound with two similar coils, one set of the three coils—viz., 76, 76^a, 76^b—being connected star fashion to the three line-wires c , d , and e between the transmitting and receiving instruments at a and b , and the other set of three coils—viz., 77, 77^a, and 77^b—being also connected star fashion to the commutator-conductors 11^a, 12^a, and 13^a of the commutator of the reply instrument. As will be seen, the two sets of coils 76, 76^a, and 76^b and 77, 77^a, and 77^b are reversely arranged—that is

to say, the common point 76^a , to which the three coils 76 , 76^a , and 76^b are connected, is arranged at the opposite side of the electromagnetic device to that at which the common point 77^a , to which the three coils 77 , 77^a , and 77^b are connected, is arranged. The electromagnetic device just described is provided with an armature 80 , that is adapted to form part of a local circuit 81 , including a battery 81^b , the winding of an electromagnetic short-circuiting device 82 , and a hand-operated switch 81^c , adapted to open and close the said circuit at a second place. The short-circuiting device 82 has an armature 82^a , that is adapted when attracted to bear simultaneously upon the three short-circuiting pins 69 , connected to the line-wires c d e , and short-circuit such wires, as and for the purpose hereinbefore described with reference to Fig. 1. The arrangement is such that normally the local circuit 81 is closed at the place where the armature 80 is located, but open at the place where the hand-operated switch 81^c is placed. Upon then sending a signal from the transmitter 25 at a to the receiver at b the coils 76 76^a 76^b will energize the cores 75 , which will attract the armature 80 against the force of gravity or a spring 80^a and move it into the open position, so as to make a second break in the 30 local circuit 81 . The said armature 80 will remain in the open position until the pointer u' of the reply instrument has been moved by the corresponding commutator-handle t' into a position corresponding to the signal sent, 35 whereupon, as the commutator of the reply instrument corresponds exactly to that of the transmitting instrument, the current from the battery y^2 will be caused to pass through the other set of coils 77 77^a 77^b in the proper order 40 and direction to neutralize the action on the cores 75 of the coils 76 76^a 76^b , so that such cores will then be demagnetized and release the said armature 80 and allow it to move into its closed position and close one break in the 45 local circuit. Thus if, for example, when an order has been sent the main-line current passes through the coil 76^b and returns through the two parallel coils 76 and 76^a , as indicated by the arrows a' , then when the commutator of 50 the reply instrument has been turned to the required distance to bring the pointer u' opposite the corresponding signal on the dial v' of the reply instrument current will be caused to flow through the coil 77^b and re- 55 turn through the two coils 77 and 77^a , as indicated by the arrows b' ; but as the one set of coils is arranged reversely to the other set the current flowing through one set will neutralize that flowing through the other set, and 60 so release the armature 80 and allow it to move into the closed position, as stated. Upon then closing the second break in the local circuit 81 by closing the hand-switch 81^c the short-circuiting device 82 will automatically 65 attract its armature 82^a and cause the same to bear against the pins 69 , thereby short-circuiting the line conductors c , d , and e ,

with the same result as before—viz., of opening the local circuit l , disconnecting the transmitting instrument from the line conductors 70 c d e , and allowing the indicator g to return to its zero position, thereby indicating that the signal has been properly received and understood.

The receiving instrument at b may be of 75 various kinds. Figs. 6 and 7 show one construction of receiving instrument which may advantageously be used. It has a rotary current-motor comprising three pairs of oppositely-arranged field-magnet coils 43 , 43^a , and 43^b , corresponding to the pairs of coils c , d , and e in Fig. 1, the coils having straight iron cores 44 arranged horizontally and parallel to one another in a circular row and an armature consisting of two sector-shaped pieces 85 45 of iron that are preferably of an angular width of about sixty degrees and are arranged directly facing each other and so as to rotate within the two circular rows of projecting core ends and are fixed to an iron spindle 46 , 90 that traverses a fixed polarizing-coil 47 , arranged between the armature-segments 45 . The spindle is provided with an indicator or pointer 48 and, if necessary, with adjustable weights 49 so arranged as to balance the 95 weight of the armature-sectors 45 , so that the armature shall be balanced and free to readily turn to and remain in any position into which it is moved. The armature-spindle 46 may conveniently be mounted in a non-magnetic 100 metal frame 50 , that carries the polarizing-coil 47 and is adapted to be inserted in place within the field-magnet 43 44 of the motor and to be fixed to the dial-plate 51 of the receiving instrument, on which are marked orders or signals corresponding to those on the dial of the transmitting instrument. The polarizing-coil 47 may be arranged to be brought into the local circuit l , Fig. 1, closed by the relay. For this purpose one end of the said coil 47 may be 110 connected, through the said frame 50 and the metal-work 50^a of the receiving instrument and a conductor 50^b , to the armature 52 of the relay at h , Fig. 7, the other end of the polarizing-coil being connected to an insulated pin 115 53 , arranged to bear at one end against an insulated spring-contact 54 . This contact is carried by the framework of the motor and is adapted to be connected, as by a conductor 54^a , to one pole of the battery 55 , the other pole of which is connected, through the bell m , to an insulated contact-screw 56 , against which the relay-armature 52 is brought when the relay 63 64 is energized, as hereinbefore described. By the construction of receiving 125 instrument described the armature 45 46 and polarizing-coil 47 can be readily inserted within or removed from the field-magnet of the motor without disturbing the latter. Figs. 8 and 9 show another construction of receiving instrument. In this case the six cores 44 of the six field-coils 43 are arranged at an angle to one another in an annular row, so as to form a hexagonal figure, the adjacent

ends of the cores 44 being held in place by six grooved rods 58. In this case the armature-sectors 45 are arranged diametrically opposite to each other. In other respects the armature and its polarizing-coil 47 may be arranged as in the construction of receiving instrument shown in Figs. 6 and 7. In each case the armature-spindle 46 should project equally from each end of the polarizing-coil 47 to prevent an end thrust being imparted thereto when the said coil is energized. Also there may be provided in connection with the armature-spindle in each case a brake device that is operated magnetically to release the spindle when the coil is energized and is applied mechanically to hold the armature in place when the receiving instrument is disconnected from the transmitting instrument and the circuit of the polarizing-coil is consequently opened. For this purpose one end of the armature-spindle 46 may, as shown in Fig. 10, be embraced by a brake-strap 59, carried by a spring-blade 60, that is provided with an armature 61, arranged opposite a projecting end of a fixed hollow iron core 62, upon which the polarizing-coil 47 is wound and through which the said armature-spindle extends, the arrangement being such that the brake-strap 59 will be moved away from the armature-spindle 46 when the core 62 is magnetized and applied to the armature-spindle by the spring-blade 60 when the core is demagnetized. In this case the armature-spindle 46 may carry only one armature-sector 45, and the field-magnet cores 44, when these are parallel to one another, as shown, may be magnetically connected together at one end—as, for example, by an iron ring 44^a. Figs. 11 to 15, inclusive, show one construction of commutator according to this invention suitable for transmitting twenty-four different signals. It comprises two annularly-arranged sets of contacts fixed upon a rotary cylindrical block 83, of insulating material, that is secured upon a suitably-supported spindle 84, provided with an operating-handle *t*. One set of contacts, hereinafter called the "main" contacts, comprises, as shown in Figs. 13 and 15, three curved metal segments 85, 86, and 87, that are of an angular or circumferential length of about one hundred and five degrees each and are separated from one another by segments 88, of insulating material, each having an angular length of about fifteen degrees, the three metal segments 85, 86, and 87 being suitably electrically connected to the three separate line-wires *c*, *e*, and *d*, as hereinafter described. The other set of contacts, hereinafter called the "supplementary" contacts, comprises, as shown in Figs. 12 and 15, three pairs of short L-shaped metal contacts 90, 91, 90^a, 91^a, and 90^b, 91^b, the two contacts of each pair being arranged adjacent to but insulated from each other and so as to overlap one another to an angular extent of fifteen degrees and each having an angular length of thirty de-

grees, the collective angular length of the two contacts being about forty-five degrees. The three pairs of overlapping supplementary contacts are separated from each other by insulated segments 92, that may be of metal, having an angular length of about seventy-five degrees, Figs. 12 and 15. The overlapping parts of each pair of supplementary contacts are arranged opposite the insulating-segment 88 between two of the adjacent main metal contacts 85, 86, and 87. The adjacent ends of the main contacts 85 and 86 are respectively connected to the supplementary contacts 90 and 91 by conductors 93 and 94, as shown in Fig. 15. The adjacent ends of the main contacts 86 and 87 are similarly connected to the supplementary contacts 90^a and 91^a, and the adjacent ends of the main contacts 87 and 85 are similarly connected to the supplementary contacts 90^b and 91^b, respectively. Bearing upon diametrically opposite sides of the commutator, so as to make connection with the main contacts 85, 86, and 87, are two contact-brushes 95 and 96 for connection to the terminals of a battery *y*, Fig. 16, corresponding to the battery *y* in Fig. 1, the number of cells in such battery being preferably divisible by four. Bearing upon diametrically opposite sides of the commutator, so as to make connection with the supplementary contacts 90, 91, 90^a, 91^a, and 90^b, 91^b, are two other contact-brushes 97 and 98, that are to be connected to intermediate parts *y*⁴ *y*⁵, respectively, of the battery *y*, so that a quarter of the cells will be interposed between each main brush 95, 96 and the corresponding supplementary brush 97, 98, as shown in Fig. 16, the two brushes at each side of the commutator being arranged in the same plane. (See Fig. 12.) Each supplementary brush 97 and 98 is composed of two spring-blades, Figs. 11 and 16, each made of a width adapted to bear upon rather less than one-half of the width of the supplementary contacts and capable of being adjusted endwise, so that it will not come onto a supplementary contact until the corresponding main brush 95 or 96 has left the main contact to which the said supplementary contact is connected, so as to avoid short-circuiting the cells located between the pair of main and supplementary brushes. To allow of endwise adjustment, each spring-blade 110 may be formed with a slot 97^a, through which the fixing-screws 97^b extend, Fig. 11.

By the construction and arrangement described when the compound commutator is connected up, as shown in Fig. 16, to an electric generator and to the three coils or three pairs of coils *c'd'e'*, Fig. 1, of a receiving instrument of the kind hereinbefore referred to and caused to make one complete rotation the resultant magnetic field of the three coils 130 or pairs of coils, and consequently the pointer *k'* of the receiving instrument, will be caused to take up twenty-four successive positions located fifteen degrees apart and correspond-

ing to twenty-four different orders or signals on the transmitter-dial. This will be readily understood from Figs. 17, 18, 19, and 20, wherein, for the sake of simplicity, the motor of the receiving instrument is shown as having three single coils c' , d' , and e' arranged at equal angular distances to one another around a common center, and the set of main commutator-contacts and their insulating-segments are shown as of larger diameter than the supplementary contacts and their insulating-segments in order that they may be seen in these figures. The line N S at right angles to each coil represents the direction of the magnetizing force of the current traversing such coil, and the large arrows K' , K^2 , K^3 , and K^4 in Figs. 17, 18, 19, and 20, respectively, indicate the position of the resultant magnetic field due to the current flowing through the coils, and consequently the position of the armature and pointer of the receiving instrument in the four positions of the commutator shown. The main contacts 85, 86, and 87 of the commutator are shown connected to the line-wires c , e , and d , respectively, by brushes 8, 10, and 9, which respectively bear upon insulated collars 4, 6, and 5, fixed on the commutator-shaft 84 and connected to the main contacts 85, 86, and 87 by insulated conductors 1^a, 3^a, and 2^a, respectively.

The operation is as follows: Assuming the commutator to have been turned clockwise into the position shown in Fig. 17, so that the main brush 95 bears upon the main contact 86, the double brush 97 bears upon an insulating-segment 92, the main brush 96 has just commenced to bear upon the adjacent insulating-segment 88, and the double brush 98 bears upon the supplementary contacts 90^b and 91^b. Then current from three-fourths of the battery y will flow, as indicated by the arrows x , from the positive pole of the battery through the brush 95, contact 86, conductor 3^a, collar 6, brush 10, line-wire e , and receiver-coil e' to the point j , where it will divide equally and return in parallel through the two coils c' , d' , line-wires c and d , brushes 8 and 9, collars 4 and 5, and conductors 1^a and 2^a to the main contacts 85 and 87, from which it will pass by the conductors 94 and 93 to the supplementary contacts 91^b and 90^b and thence by the double supplementary brush 98 to the part y^5 of the battery y , the insulating-segment 88, on which the brush 96 then bears, preventing short-circuiting of the portion of the battery between the brushes 96 and 98. The resultant magnetic field will then be represented by the vertical arrow K' , which also represents the position of the armature and pointer of the receiving instrument. The circuit will continue to flow in the direction indicated by the arrows x , and the resultant magnetic field of the coils c' , d' , e' (indicated by the arrow K') will remain stationary until the commutator and pointer u have been turned through fifteen degrees—that is to say,

into the position shown in Fig. 18, in which the main and supplementary brushes 95 and 97 are still on the main contact 86 and insulating-segment 92, respectively; but the main brush 96 has just commenced to bear upon the main contact 85 and the double brush 98 is bearing upon the supplementary contact 90^b, which is connected to the main contact 75 70 by the conductor 93. Current will then flow through the coils c' , d' , e' back to the main contacts 85 and 87 in the same direction as before and as indicated by the arrows x' ; but from the contact 85 it will now pass by 80 the main brush 96 to the extreme right-hand end or negative pole of the battery y , while from the contact 87 it will pass by way of the supplementary contact 90^b and double brush 98 to the point y^5 of the battery. As a result 85 the strength of the current flowing through the coils c' and d' instead of being equal, as in Fig. 17, will be in the proportion of four to three, and the position of the resultant magnetic field of the three coils will be indicated by the arrow K^2 , which is fifteen degrees in advance of the arrow K' in Fig. 17 and corresponds to the angle through which the commutator has been turned. Upon again rotating the commutator in the same 90 direction as before the direction and strength of the current through the coils will remain as in Fig. 18 until the commutator has been moved through a further angle of fifteen degrees and into the position shown in Fig. 19, in which the main brushes 95 and 96 still bear upon the main contacts 86 and 85, respectively; but both of the supplementary brushes 97 and 98 bear upon the adjacent insulating-segments 92, whereupon the 105 current will flow in the direction of arrows x^2 . In this position of the commutator the coil d' will be cut out of circuit, and the full strength of the battery will flow through the coils e' and c' , which are in series, so that the resultant magnetic field of the coils and the armature and pointer of the receiver will be then shifted into the position indicated by the arrow K^3 —that is to say, through a further angle of fifteen degrees, 110 corresponding to the further angle through which the commutator has been turned. Upon again rotating the commutator in the same direction as before the direction and strength of the current, and consequently the 115 position of the magnetic resultant K^3 , will remain as in Fig. 19 until the commutator has been turned through a further angle of fifteen degrees and into the position shown in Fig. 20, in which the main brushes 95 and 96 120 still bear upon the main contacts 86 and 85, respectively, and the brush 98 still bears upon an insulating-segment 92; but one-half of the double brush 97 will be upon the supplementary contact 91^a, which is in connection 125 through a conductor 94 with the main contact 87. Current will now flow in the direction of the arrows x^3 from the positive pole and point y^4 of the battery y through the two coils e' and

d' in parallel and then through the coils *c'*, the strength of the current through the two coils *e'* and *d'* being in the proportion of four to three, so that the resultant magnetic field of the 5 three coils and the armature and pointer of the receiver will be shifted into the position indicated by the arrow *K*⁴—that is to say, through a further angle of fifteen degrees, corresponding to the further angle through 10 which the commutator has been turned. In this way by continuing the rotation of the commutator through successive angles of fifteen degrees the resultant magnetic field of the receiver - coils and the armature and 15 pointer of the receiver will be caused to move through corresponding angles of fifteen degrees at a time. By overlapping the ends of the supplementary contacts no variation in the position of the resultant magnetic field of 20 the coils of the receiving instrument, and therefore of the pointer of that instrument, will take place until the commutator has been moved through an angle of fifteen degrees from the position in which it caused the 25 pointer of the receiver to take up such position. Consequently if, as in Figs. 17 to 20, inclusive, the pointer *u* of the transmitting instrument be fixed to the commutator, so that it will be on the division-line 99 between 30 two adjacent signal-spaces 100 on its dial-plate *v* at the moment when one or other of the brushes is passing from one segment to another on the commutator, the pointer of the receiving instrument will be caused to 35 move rapidly from the center of one signal-space 100 on its dial *k*² to the center of an adjacent space at the moment when the pointer *u* of the transmitting instrument passes the division-line between the corresponding signal-spaces on its dial *v*.

By coupling up the commutator to the battery in the manner described, so that sometimes the whole of the battery and at other times only three-quarters of it is used, the 45 use of resistance devices such as have heretofore been employed for varying the strength of the current through the different coils at different times and which are objectionable can be avoided.

50 As will be obvious, a commutator of the kind above described with reference to Figs. 11 to 20, inclusive, can be used in various constructions of signaling apparatus of the kind herein referred to.

55 The overlapping of adjacent metal commutator contacts can be used in various constructions of commutators whether designed to transmit twelve, twenty-four, or other numbers of signals.

60 What I claim is—

1. Electrical signaling apparatus of the kind referred to, comprising a signal-transmitter, a signal-receiver, three line-wires connected to said receiver, a switch adapted to connect 65 said line-wires to said transmitter when the latter is operated to send a signal and to disconnect said line-wires from said transmitter

when said line-wires are short-circuited upon themselves, an indicator adapted to show when a signal has been sent and to return to the normal position when the line-wires are short-circuited, a local circuit with electric generator and signaling device at said receiver, a relay adapted on the sending of a signal to close said local circuit and on the short-circuiting of the line-wires to open said local circuit, and a short-circuiting device whereby said line-wires can be short-circuited upon themselves, substantially as described for the purposes specified.

2. In electrical signaling apparatus of the kind referred to, the combination of a signal-transmitter comprising a rotary commutator provided with a pointer and operating means and composed of two sets of contacts that are movable relatively to one another, and a dial bearing the signals to be sent and over which said pointer moves, an electric generator connected to one set of contacts, three conductors connected to the other set of contacts, a signal-receiver comprising an electric motor having a rotary field and a rotary armature provided with a pointer, and a dial bearing signals corresponding to those on the dial of the signal-transmitter and over which the last-mentioned pointer is mounted to move, three line-wires connected to the electric motor of said receiver, a switch device adapted to connect the three line-wires to the said three conductors when the signal-transmitter is operated to send a signal, electromagnetic means adapted to then automatically hold said switch device in the operative position until the line-wires are short-circuited upon themselves and to then release said switch device and disconnect the line-wires from said conductors, an indicator adapted, on the operation of said switch device to send a signal, to indicate that a signal has been sent, an electrically-operated signaling device located at the signal-receiver, a relay connected to said line-wires and adapted to close the circuit of said signaling device when a signal is sent, and a short-circuiting device whereby said line-wires can be short-circuited upon themselves, substantially as described.

3. In electrical signaling apparatus of the kind referred to, the combination with the signal-transmitter having a commutator and three conductors connected thereto, and the signal-receiver and three line-wires connected thereto, of an automatic switch adapted to connect said three conductors to said three line-wires, said switch comprising armatures that normally disconnect said conductors from said line-wires but are capable of connecting the same together when moved into the closed position, an electromagnetic device the circuit of which is adapted to be temporarily closed when the transmitter is operated to send a signal and to then move said armatures into the closed position, an electromagnetic device adapted to be energized on the connection of the line-wires to

the commutator-conductors and to hold said armatures in the closed and operative position but to release said armatures and allow them to move into the open position when the 5 line-wires are short-circuited upon themselves, and a short-circuiting device located at the receiver and adapted to short-circuit said line-wires, substantially as described.

4. In electrical signaling apparatus of the 10 kind referred to, the combination with a transmitter having a rotary commutator, three conductors leading therefrom, and a receiver with rotary-field motor, and three line-wires *c*, *d* and *e* connected to said motor, of an automatic switch for connecting said line-wires to said conductors, said switch comprising a number of coils provided with iron cores and arranged in two sets of three each, two armatures 22 and 23 arranged between the polar 20 ends of said cores, two contacts connected to the line-wires *c* and *d* respectively and against which said armatures abut when attracted by one set of cores, and a local electric circuit adapted to be temporarily closed each time 25 the transmitter is operated to send a signal and to be opened each time the pointer of the transmitter comes opposite a signal on the signal-dial, one of the coils in one set thereof being arranged in said local circuit, another 30 of the coils in said set being connected at its two ends to the line-wires *c* and *e* respectively, and the other coil in the set being connected at its two ends to the line-wires *d* and *e* respectively, the three coils in the other set 35 of coils being weaker than the coils in the first-mentioned set of coils and arranged to respectively form part of three of the commutator-conductors whereof two are connected to the two armatures 22 and 23 respectively and the other commutator-conductor 40 is connected to the line-wire *e*, and a short-circuiting device located at the receiver and whereby said line-wires can be short-circuited upon themselves, substantially as described 45 for the purpose specified.

5. In electrical signaling apparatus of the kind referred to, the combination with a transmitter having a rotary commutator and three conductors leading therefrom, a receiver with 50 rotary field-motor, and three line-wires *c*, *d* and *e* connected to said motor, of an electromagnetic switch adapted, on the operation of said transmitter to send a signal, to automatically connect the line-wires and commutator-conductors together as set forth and to disconnect the line-wires from said commutator-conductors when said line-wires are 55 short-circuited upon themselves, a switch-indicator comprising a pointer, a dial over which 60 said pointer can move, and an armature connected to said pointer and arranged in proximity to said electromagnetic switch so as to be operated thereby when the same is magnetized, and a short-circuiting device where- 65 by said line-wires can be short-circuited upon themselves, substantially as described.

6. In electric signaling apparatus of the

kind referred to, the combination with the transmitting instrument and three line-wires for connection thereto, of a receiving instrument comprising a case having a signal-dial corresponding to that of the transmitting instrument, an electric motor fixed within said case and having a field-magnet composed of three connected pairs of coils connected to 75 said line-wires and provided with iron cores arranged around a center, and an armature comprising a sector-shaped piece of iron and an iron spindle to which the same is fixed, a pointer connected to said spindle and arranged to move over said dial, a polarizing-coil surrounding said spindle, means for energizing said coil, and a separate frame carrying said armature and polarizing-coil and adapted to be inserted within said field-magnet and to be fixed to said case independently of said field-magnet, substantially as described.

7. In electric signaling apparatus of the kind referred to, the combination with the 90 transmitting instrument and three line-wires for connection thereto, of a receiving instrument comprising a case having a signal-dial corresponding to that of the transmitting instrument, an electric motor fixed within said 95 case and having a field-magnet composed of three connected pairs of coils connected to said line-wires and provided with iron cores arranged around a center, and a balanced armature composed of sector-shaped pieces of iron 100 and an iron spindle to which they are fixed, a pointer connected to said spindle and arranged to move over said dial, a polarizing-coil surrounding said spindle between said sector-shaped pieces of iron, a separate frame 105 carrying said armature and polarizing-coil and adapted to be inserted within said field-magnet and to be fixed to said case independently of said field-magnet, a local electric circuit including said polarizing-coil, and a relay adapted to be brought into action when 110 a signal is sent and to complete said local circuit, substantially as described.

8. In electric signaling apparatus of the kind referred to, a receiving instrument comprising a case having a signal-dial, an electric motor having an annular field-magnet, a rotary armature arranged within said field-magnet and provided with a spindle, a pointer fixed to said spindle and arranged to move 120 over said dial, a metal frame carrying said armature and adapted to be inserted within said field-magnet and to be fixed to said case independently of said field-magnet, a polarizing-coil carried by said frame and having 125 one of its ends fixed to said frame and its other end to an insulated pin, an insulated spring-contact carried by the framework of said motor and bearing against said pin, a relay adapted to be energized when a signal 130 is received and having an armature connected to said frame, a fixed contact against which said relay-armature bears when the relay is energized, and an electric battery

having one pole connected to said spring-contact and the other pole to said fixed contact, substantially as described.

9. In an electric signaling apparatus of the kind herein referred to, the combination with transmitting and receiving instruments and three line-wires for connecting the same, of a local electric circuit at the receiving instrument, a signaling device in said circuit, 10 and a relay adapted to close said local circuit when a signal is sent, said relay comprising three coils connected star fashion to said three line-wires and provided with iron cores, and a pivoted armature adapted, when attracted by said cores, to close said local circuit, substantially as described.

10. In an electric signaling apparatus of the kind referred to, the combination with the transmitting and receiving instruments 20 and three line-wires connected to the receiving instrument, of an electromagnetic switch adapted to automatically connect said line-wires to said transmitter when the latter is operated to send a signal and to disconnect 25 said line-wires from said transmitter when said line-wires are short-circuited upon themselves, and a short-circuiting device located at the receiving-station and comprising three fixed contacts connected to the respective 30 line-wires, and a movable contact adapted to be caused to bear simultaneously upon the three fixed contacts, substantially as described.

11. In an electric signaling apparatus of 35 the kind referred to, the combination with the transmitting and receiving instruments, three line-wires connected to the receiving instrument, an electromagnetic switch adapted to connect said line-wires to the transmitting instrument when the latter is operated to send a signal and to disconnect said line-wires from said transmitting instrument when the line-wires are short-circuited upon themselves, a local electric circuit with signaling device located at the receiving-station, 40 a relay connected to said line-wires and adapted to close said local circuit when a signal is sent and to open said local circuit when the line-wires are short-circuited upon themselves, a short-circuiting device for short-circuiting said line-wires upon themselves, and a reply instrument corresponding to the transmitting instrument and provided with controlling means adapted to prevent the 45 short-circuiting of said line-wires and the opening of said local circuit until the pointer of said reply instrument has been moved opposite to the signal sent, substantially as described.

60 12. In an electric signaling apparatus of the kind referred to, the combination with the transmitting and receiving instruments, three conductors connected to the transmitting instrument, and three line-wires connected to the receiving instrument, of an electromagnetic switch adapted to connect said line-wires to said conductors when the

transmitting instrument is operated to send a signal and to disconnect said line-wires from said conductors when the line-wires are short-circuited upon themselves, a local electric circuit with signaling device located at the receiving-station, a relay connected to said line-wires and adapted to close said local circuit when a signal is sent and to open said local circuit when the line-wires are short-circuited, a short-circuiting device for short-circuiting said line-wires upon themselves, and a reply instrument corresponding to the transmitting instrument and provided with three conductors extending therefrom and with controlling means adapted to prevent the short-circuiting of said line-wires and the opening of said local circuit until the pointer of said reply instrument has been moved opposite to the signal sent, said controlling means consisting of an electromagnetic device comprising three iron cores each wound with two coils, and an armature adapted to be released by said cores when the electric currents flowing through the two sets of coils neutralize each other, one set of the three coils being connected star fashion to the three line-wires and the other set of three coils being connected star fashion but in the reverse order to the three conductors extending from said reply instrument, a second local electric circuit that is opened at one point by said armature and kept open so long as the current flowing through one set of said coils is not neutralized by the current flowing through the other set of coils, and is closed by said armature when the currents through the two sets of coils neutralize each other, an electromagnetic device having its winding arranged in said second local circuit and adapted when energized to operate said short-circuiting device, and a hand-operated switch adapted to open and close said second local circuit at a second place therein, substantially as described for the purpose set forth.

13. In electric signaling apparatus of the kind referred to, a transmitting instrument having a dial bearing the signals to be sent, 115 a rotary commutator, means for operating the same, and a pointer connected to said commutator and arranged to move over said dial, said commutator comprising a rotary insulating-block, three main contacts 85, 86, 120 and 87 with interposed insulating-segments 88, three sets of pairs of supplementary contacts 90, 91, 90^a, 91^a, and 90^b, 91^b, arranged adjacent to but insulated from each other and having their adjacent ends overlapping one 125 another, insulating-segments 92 between said pairs of supplementary contacts, said main and supplementary contacts with interposed insulating-segments being fixed upon said rotary block and being relatively arranged and connected as described, two contact-brushes arranged to make connection with the main contacts and with the terminals of an electric battery, two other contact-brushes arranged

to make connection with the supplementary contacts and with intermediate parts of said battery, each of these latter brushes being composed of two blades each of a width less than that of the overlapping parts of said supplementary contacts and arranged to come into connection with a supplementary contact only after the main contact to which said supplementary contact is connected has left the corresponding main brush, and three line conductors connected to the respective main contacts, substantially as described.

14. In electric signaling apparatus of the kind referred to, the combination with a signal-receiving instrument having a rotary-field electric motor, a signal-dial, and a pointer connected to the armature of said motor and arranged to move over said dial, and an electric battery, of a signal-transmitting instrument having a dial bearing the signals to be sent, a rotary commutator, means for operating the same, and a pointer connected to said commutator and arranged to move over said dial, said commutator comprising a rotary insulating-block, three main contacts 85, 86 and 87 each of an angular length of about one hundred and five degrees with interposed insulating-segments 88 each of an angular length of about fifteen degrees, three sets of pairs of supplementary contacts 90, 91, 90^a, 91^a, and 90^b, 91^b, arranged adjacent to but insulated from each other and having their adjacent ends overlapping one another to an angular extent of about fifteen degrees, each of said supplementary contacts being of an angular length of about thirty degrees, insulating-segments 92 between said pairs of supplementary contacts, said main and supplementary contacts with interposed insulating-segments being fixed upon said rotary block and being relatively arranged and connected as described, two contact-brushes arranged to make connection with the main contacts and with the terminals of said electric battery, two other contact-brushes arranged to make connection with the supplementary contacts and with intermediate parts of said battery so as to include one-quarter of the battery between each adjacent pair of main and supplementary brushes, each of said supplementary brushes being composed of two blades capable of endwise adjustment and each of a width less than that of the overlapping parts of said supplementary contacts and arranged to come into connection with a supplementary contact only after the main contact to which said supplementary contact is connected has left the corresponding main brush, and three line conductors for connecting the respective main contacts to said receiving instrument, all substantially as described for the purpose specified.

15. In electric signaling apparatus of the kind referred to, the combination with a sig-

nal-receiving instrument having a rotary-field electric motor, a signal-dial, and a pointer connected to the armature of said motor and arranged to move over said dial, and an electric battery, of a signal-transmitting instrument having a dial bearing the signals to be sent, a rotary commutator, means for operating the same, and a pointer connected to said commutator and arranged to move over said dial, said commutator comprising a rotary insulating-block, three main contacts 85, 86 and 87 each of an angular length of about one hundred and five degrees with interposed insulating-segments 88 each of an angular length of about fifteen degrees, three sets of pairs of supplementary contacts 90, 91, 90^a, 91^a, and 90^b, 91^b, arranged adjacent to but insulated from each other and having their adjacent ends overlapping one another to an angular extent of about fifteen degrees, each of said supplementary contacts being of an angular length of about thirty degrees, insulating-segments 92 between said pairs of supplementary contacts, said main and supplementary contacts with interposed insulating-segments being fixed upon said rotary block and being relatively arranged and connected as described, two contact-brushes arranged to make connection with the main contacts and with the terminals of said electric battery, two other contact-brushes arranged to make connection with the supplementary contacts and with intermediate parts of said battery so as to include one-quarter of the battery between each adjacent pair of main and supplementary brushes, each of said supplementary brushes being composed of two blades capable of endwise adjustment and each of a width less than that of the overlapping parts of said supplementary contacts and arranged to come into connection with a supplementary contact only after the main contact to which said supplementary contact is connected has left the corresponding main brush, and three line conductors for connecting the respective main contacts to said receiving instrument, all substantially as described for the purpose specified.

Signed at Fenchurch street station, London, E. C., this 1st day of January, 1901.

ALFRED UPTON ALCOCK.
